UNITED STATES PATENT OFFICE.

EMIL C. DANNER, OF WESTMONT BOROUGH, PENNSYLVANIA.

BUNDLING.

1,321,092.

Specification of Letters Patent.

Patented Nov. 11, 1919.

Application filed January 13, 1919. Serial No. 270,809.

To all whom it may concern:

Be it known that I, EMIL C. DANNER, a citizen of the United States, residing in the borough of Westmont, in the county of Cambria and State of Pennsylvania, (whose post-office address is Johnstown, Pennsylvania,) have invented certain new and useful Improvements in Bundling; and I do hereby declare the following to be a full, clear, and 10 exact description, such as will enable others skilled in the art to which it appertains to make and use the same.

My invention relates to improvements in means, method and bundles, particularly of 15 certain kinds of steel products with special reference to what are known as rail anchors, each of which in general consists of a flat piece of spring steel with the intermediate portion cut away so as to form an approximately 20 rectangular notch with longitudinally and laterally extending portions surrounding substantially three sides of the same. Heretofore such material has been packed loosely and indiscriminately in 25 boxes, burlap or in casks, all of which is expensive and unsatisfactory for handling, checking and counting, and the packages made in this way are generally too heavy 30 for one man to handle without the use of mechanical appliances of some kind.

My improvement consists in means for making neat and strong bundles of such materials by nesting the same together in a compact form whereby the different portions 35 interlock and prevent relative disarrangement, this being accomplished on a specially prepared table or platform provided with cleats spaced apart or grooves for the tie wires while a bundle is being assembled, 40 after which the ends of the tie wires are brought together and twisted, making a compact and secure package which can be handled by one man, takes up the minimum amount of room and is so strong that it will 45 not become broken in rough handling or dropping.

Having thus given a general description 50 of my invention, I will now, in order to make the matter more clear, refer to the annexed sheet of drawings, which forms part of this specification and in which like characters denote like parts:—

Figure 1 is a top plan view of a portion 55 of the work receiving table showing the position of the binding or tie wires at the beginning of the assembling. Fig. 2 is a top

plan view of the same portion of the table after piling or assembling the rail anchors, before the bundle is tied. Fig. 3 is a perspective view of the complete bundle after 60 tying the same. Fig. 4 is a side elevation of one of the rail anchor plates, and Fig. 5 is a top plan view of an anchor plate.

Referring now to the characters of reference on the drawings:—1 is a portion of 65 the top of the assembling table as viewed in plan, 2 are cleats secured thereto spaced apart as shown to provide two grooves 3 and 4 adapted to receive the binding wires 5 and 6, and it will be readily understood that instead of using these cleats I may provide 70 grooves in the body of the table itself. As illustrated in Fig. 3, the wires 6 are tied or twisted in a coil or knot 7, thus drawing them firmly in place and similarly the 75 wires 5 are tied or twisted in a knot 8, these wires, as noted, being located in the reentrant angles at the side corners of the bundle and are thereby absolutely secure from displacement and also protected from breakage 80 or wear, besides which the projecting ends of the knots or twists are protected by the outstanding portions of the bundle so that these will not catch in the clothing or hands of those handling them, nor any 85 other objects with which they may come in contact. The special rail anchors to be bundled are indicated generally as 9, each provided with a notch 10 or cutaway portion, 11 being the main longitudinal portion, 13 90 one of the projecting end portions, 14 the other projecting end portion, 15 the interior notch in the anchor with the inwardly projecting portion 16 adjacent thereto. The rail anchors are nested together in groups or 95 sets with their sides adjacent but not necessarily exactly parallel on account of the taper of the anchors in general, these being assembled in groups or sets consisting of a lower course 17 with the notches opening 100 or extending upwardly and a superimposed course 18 with the notches opening or extending downwardly, the projecting ends 13 and 14 overlapping the outer longitudinally extending portions 11, thus securing 105 the plates of each course firmly together. The width of the upper course of plates 17 is made such that it fits with reasonable tightness within the space of the notches of the course 18. A number of these layers are 110 prepared and superimposed upon each other, each pair of two sets consisting pref-

erably of twenty-five plates so that two pairs will consist of fifty plates, or four will consist of one hundred plates which are, therefore, easily counted and checked. The bundle is also of such size as to be easily handled by one man and as it is substantially cubical in general outline it can be packed in the least space possible on board cars, ships, wagons, in warehouses, or elsewhere, 10 all of which conduces to ease and economy.

Although I have shown tie wires for securing the bundle together, I may use strips of board or similar material nailed or otherwise secured together, with or without band 15 steel reinforcements.

Although I have described and illustrated my invention in considerable detail, I do not wish to be limited to the exact and specific details thereof as shown and described, but may use such modifications in, substitutions for, or equivalents thereof, as are embraced within the scope of my invention, or as pointed out in the claims.

Having thus described my invention, 25 what I claim and desire to secure by Letters Patent is:—

1. A bundle of rail anchors comprising a set of pieces, each having an intermediate notch therein of approximately rectangular 30 outline assembled side by side with the notches in substantial registry, a set of notched pieces similarly assembled with their substantially registered notches extending in the opposite direction, so placed 35 together that the laterally extending por-

tions of each set are adjacent to and adapted to contact with the outer side portions of the other set and means for securing the same in said relative positions.

2. A bundle of rail anchors comprising 40 a set of pieces, each having an intermediate notch therein of approximately rectangular outline assembled side by side with the notches in substantial registry, a set of notched pieces similarly assembled with 45 their substantially registered notches extending in the opposite direction, so placed together that the inner edges of the longitudinal portions are superimposed and the laterally extending portions of each set are 50 adjacent to and adapted to contact with the outer side portions of the other set, and means for securing same in said relative positions.

3. A bundle of rail anchors comprising a 55 set of pieces, each having an intermediate notch, assembled in substantial registry, a similar set of assembled pieces with their substantially registered notches extending in the opposite direction, so placed together 60 that the laterally extending portions of each set are adjacent to and adapted to contact with the outer side portions of the other set, and means extending in the external reentrant angles for securing same in said relative positions.

In witness whereof I hereunto affix my signature.

EMIL C. DANNER.
